Alfonsine Taffert

Attorney

UNITED STATES PATENT OFFICE.

OLE MOLSKNESS, OF COLMAN, SOUTH DAKOTA.

RAILROAD-CROSSING SIGNAL.

Application filed August 18, 1922. Serial No. 582,757.

To all whom it may concern:

Be it known that OLE MOLSKNESS, a citizen of the United States of America, residing at Colman, in the county of Moody and 5 State of South Dakota, has invented new and useful Improvements in Railroad-Crossing Signals, of which the following is a specification.

The object of the invention is to provide a 10 simple and efficient danger signal for use at grade crossings as a protection to pedestrians and drivers on roads intersecting the railway affording a permanent means of indicating the existence of the crossing and a 15 special means of indicating the approach of a train, and more particularly to provide an apparatus of this type which is entirely mechanical in its construction and does not rely upon electrical, pneumatic or other energy and which by reason of its simplicity 20 is not subject to disarrangement and therefore failure to operate when required; and with these objects in view the invention consists in a construction and combination of 25 parts of which a preferred embodiment is shown in the accompanying drawings, wherein:—

Figure 1 is a plan view, and

Figure 2 is a side view of an apparatus 30 embodying the invention applied in the operative position to a railway crossing or intersection, the train signal in Figure 2 being in the normal or housed position.

Figure 3 is a view similar to Figure 2 35 showing the train signal in its exposed or warning position.

Figure 4 is a transverse section to disclose more clearly the construction of the wheel 40 actuated trip for operating the plunger 36.

Figure 5 is a view of the releasing trip.

Figure 6 is a view of the crossing signal, 45 showing the plunger 36 and illustrating a modified embodiment of the signal wherein the wire or cable 38 is employed as connect- ed direct with the latch 37.

Figure 7 is a view of a modified form of 50 rocker 41 which performs the same function as the trip 26^a.

Figure 8 is a view in elevation of the device shown in Figure 7.

Figure 9 is a view of a portion of the track, showing the lever 34 in section and the wheel engaging arcuate tread 35.

Figure 10 is a view of the rocker 27, showing 55 its weighted end and its connection with the plunger 19.

Figure 11 is a view also showing the rocker 27 and the trip 28.

Figure 12 is a plan view of the signal 60 housing and the danger signal 14.

Figure 13 is a cross sectional view on line 13—13 of Figure 12.

The apparatus embodies a permanent 65 crossing signal unit 10 consisting of spaced plates supported by a suitable arm 11 from a post or standard 12 erected at one side of the line of the track rails 13 provided on their remote or outwardly facing surfaces with warning symbols such as the words "Railroad crossing" or the equivalent there- 70 of, and movably mounted between said plates or elements of the permanent signal is a train signal plate 14 carried for example by an arm 15 pivotally mounted in the construction illustrated at 16 upon an extension 75 of the arm 11 which may be suitably braced as indicated at 17.

Connected by means of a link 18 with the arm 15 which supports the train signals (provided with any suitable warning signal 80 such as the word "Danger") is a plunger rod or bar 36 having a catch member 20 for engagement with a latch 21 yieldingly held in the path of movement of the catch and having a beveled under surface as indicated so 85 that an upward movement of the catch will result in the repression of the latch and an engagement therewith to maintain the train signal in an elevated position where it is housed between and concealed by the elements of the stationary signal 10. The latch 90 95 21 is spring actuated and may as illustrated have a resilient arm 22 attached to the post or standard or may be otherwise mounted to yieldingly maintain the engaging element thereof in the path of movement of the catch which to facilitate engagement may move a bearing roll 23.

In the embodiment of the invention which is illustrated in Figures 1 to 5 inclusive the 100 means for operating the latch to release and permit the exposure of the train signal upon the approach, in either direction, of a train on the track, includes a lever 24 pivoted at 25 and having attached to its extremities the 105 flexible connections 26 consisting for example of wires or cables which extend to wheel actuated trips 26^a located on the track at suitable distances on each side of the crossing. For releasing the train signal 110 there is employed a train actuated trip located remote from the crossing consisting

of a rocker shaft 27 having a trip finger 28 located sufficiently close to a track rail to be engaged by the wheel of a car traversing the latter and yieldingly held in position by a 5 weighted arm 29, said rocker having a crank arm 30 connected with the lower end of a plunger rod or bar 19 which is held to move in a fixed path by means of a suitable guide

31. The lower end of the plunger rod 10 preferably carries a cushioning spring 32 for engagement by the crank arm and the plunger rod is preferably provided with a stop 33 for engagement with the guide 31 to limit the downward movement of the plunger 15 so that when the trip finger is swung in one direction by the movement of a car and when swung in the opposite direction will move idly and will return to its normal position with the trip finger in its vertical position 20 by the action of the counterweight 29.

There are preferably two releasing trips disposed on opposite sides of the crossing, as shown, each having an independent flexible connecting member 26.

25 The signal resetting trip as illustrated consists of a lever 34 having an arcuate tread 35 arranged in the path of wheels traversing the track rail and is connected to the rod 36 which carries the catch member 20 which, 30 in turn, cooperates with the latch 21 to which the flexible connection 26 is attached.

In the modified construction illustrated in Figures 6 and 7 the construction, mounting and control of the signal elements correspond substantially with those hereinabove described but the connection between the latch 37 and the wheel actuated releasing trip at opposite sides of the crossing consists of a flexible connection such as a wire or 40 cable 38 extended from the latch around a direction pulley 39 on the standard or post and a second direction pulley 40 near the base of the post or standard from which it may run under-ground or close to the track 45 rails to the trip, under conditions rendering an overhead connection objectionable. In this construction the trip consists of a rocker shaft 41 having a trip finger 42 normally and yieldingly held in an upright position 50 and therefore in the path of wheels traversing the track by means of a depending weighted arm 43 to which the flexible connections are attached so that when the trip

finger is swung toward the crossing by an approaching train the signal is released 55 whereas a swinging movement of the trip finger in the opposite direction or away from the crossing as by the wheels of the train after leaving the crossing, the rocking movement does not effect the trip mechanism. 60

Having described the invention, what is claimed as new and useful is:—

1. A railway crossing signal apparatus having a normally housed movable train signal element, a catch having connection with said signal element, a yielding latch for engagement by the catch to hold the said signal element in its housed position, wheel actuated trips arranged on the line or track 70 and operatively connected with the latch for releasing the signal element, and a resetting mechanism having a wheel actuated element for returning the signal element to its housed positions, the resetting mechanism having a plunger bar carrying said catch and operatively connected with the danger signal element and also including a rocker having a trip finger in the path of wheels traversing a track rail, said rocker being 80 counterweighted and having an operative connection with the plunger bar. 75

2. A railway crossing signal apparatus including a housing with crossing notices on opposite sides, a train signal element movable into and from the housing, a spring-leaf latch with a shoulder, a catch member operatively connected to the train signal element and adapted to engage with said shoulder to retain the signal element in its housed position, a wheel actuated trip disposed adjacent the track rail and operatively connecting with the latch to actuate the same and release the catch member to permit the train signal to assume exposed or danger positions. 95 and a rocker with a wheel actuated means on one end and including a plunger bar at the other end and carrying the catch member for restoring the catch member in engagement with the shoulder of the latch, thereby 100 acting to retain the danger signal in its housing.

In testimony whereof he affixes his signature.

OLE MOLSKNESS.
